FAN

Herman C. Hueglin, Chicago, Ill., assignor to
 Federal Merchandise Company, Chicago, Ill.,
 a corporation of Illinois

Application May 9, 1935, Serial No. 20,520

4 Claims. (Cl. 230—261)

This invention relates to fans, and particularly to fans for use in circulating air as, for example, in ventilators and the like.

It is to be understood, however, that the fan 5 of the present invention is not limited to use in ventilators, nor to operation on air, but may be employed elsewhere as suitable or desired.

Where the fan is used in a ventilator, the ventilator may comprise a fan and a driving motor 10 provided with a bracket for mounting the fan and motor in a panel, which panel may, in turn, be adapted for mounting in or over a window or other opening, or the fan may be used in connection with a stand or pedestal such as that 15 shown in my copending application, Serial No. 17,562, filed April 22, 1935, or otherwise as suitable or desired.

The present invention has for one of its objects the provision of a fan having means for 20 preventing the fan from drawing air in centrally from the discharge side.

Another object is to form pockets for the air which is thrown off the blades by the centrifugal motion, the tips of the blades beyond the 25 pockets throwing the air forward and, with the present improvement, providing a much greater velocity of air at the outside margins of the pockets.

Another and more specific object is to form the 30 pockets above referred to and prevent the fan from drawing air in centrally from the discharge side by the simple expedient of a disc centrally disposed and secured in place to the discharge side of the fan, and, still more specifically, by 35 means of a disc centrally disposed and secured in place to the discharge side of a fan having blades with inner scooped or bucket-shaped portions behind the disc and outer blade portions extending outwardly from the periphery of the disc 40 and adapted for throwing the air forward.

Further objects and the advantages and details of the illustrated embodiment of the invention will appear from the following detailed description, taken in connection with the accompanying drawing, in which:

Figure 1 is a perspective view of a fan embodying the present invention;

Figure 2 is an elevational view of the discharge side of the fan, with the centrally disposed disc secured thereto partially broken away to reveal the means on one of the blades for attachment of the disc thereto; and

Figure 3 is a more or less diagrammatic longitudinal section showing how the fan is prevented from drawing air in centrally from the dis-

charge side and how the air is pocketed centrally, moved outwardly, and then forward by the blade portions beyond the periphery of the disc.

Referring to the drawing, the fan selected for illustration comprises a collar or hub portion 10 which is substantially cylindrical in form and which is bored centrally thereof, as shown in Figure 1, to form a cylindrical bearing portion 11 adapted to receive a rotating shaft or the like to which the fan is secured.

A set screw 12 is threaded into the collar 10 radially thereof and is provided with a polygonal recessed head opening for insertion of a suitable tool to thread the set screw with respect to the shaft to secure the fan firmly to the shaft for rotation therewith. Integral with the forward end of the hub 10 is the hub or central portion 14 of the fan proper, which hub portion 14 has the integral fan blades 15 extending radially outwardly therefrom. The fan shown has five 20 blades, but it is to be understood that the number of blades may be varied within the scope of the present invention.

The structure of the fan proper is similar to the structure of the fan shown in my copending 25 application, Serial No. 704,826, filed January 2, 1934. The blades 15 are integrally connected to the hub portion 14 by means of the relatively small angularly extending tapered portions 16 of the blades, which produces a hub of relatively 30 small area and also reduces the quantity of metal required. Substantially the entire outer portion 17 of each blade 15 from the tip 18 to the section indicated at 19 is of the same curvature and pitch. These outer blade portions 17 may 35 be of relatively slight forwardly directed concave formation from one radial edge of each blade 15 to the other edge of the blade, or the concavity may be decreased to such an extent as to provide substantially planar surfaces if desired. In the 40 illustrated embodiment of the invention, all sections of each blade 15 between the tip 18 and the section 19 are substantially identical, and the outer portion of each blade is thus rendered uniform in pitch and curvature throughout its en- 45 tire length.

The remainder or inner portion 20 of each blade 15, between the section 19 and the tapered connecting portion 16, is of scooped or bucket-shaped formation. From the section 19, the 50 blade is hollowed out inwardly and reaches its greatest concavity at the section 21 approximately midway between the section 19 and the outer end of the tapered connecting portion 16 between the blade and the hub of the fan. The pitch 55

angle of this scooped or bucket-shaped inner portion 20 of the blade inwardly of the section 19 is preferably increased so that the blade has a slightly warped effect at this point. This 5 pitch angle preferably continues to increase and is preferably increased to the maximum just outwardly of the outer end of the tapered connecting portion 16.

At about the section 21 the blade 15 also preferably has its greatest concavity in a transverse direction, as shown. It is thus apparent that from the section 19 to the section 16, the blade is hollowed out to give it a great concavity and, at the same time, is slightly warped to increase the 10 pitch thereof. At the section 16, connecting the blade to the hub, the pitch angle has increased to approximately 75°, whereas the pitch angle of the outer portion 17 of the blade is approximately only 15 35° and remains at this angle from the outer tip 18 until the section 19 is reached. From this point 20 or section 19, there is a progressive increase in pitch, with a maximum concavity at the section 21, and a decreasing concavity from there to the section 16.

At the point 16, where the blade joins the hub, the blade is of relatively small lateral extent. However, the metal is preferably thickened at this point to provide the necessary support and rigidity for the blade, but the surface adjacent the hub has 25 been, to a large extent, eliminated by increasing the pitch angle and decreasing the lateral extent of the blade at the same time, there being a sharp taper from the section 20 to the section 16, as shown. The blade 15 has its greatest lateral extent adjacent the section 21, which is the bottom or concave portion of the bucket-shaped inner portion of the blade.

A thin sheet-metal disc 25 of a diameter to cover the outer sides of the inner concave or bucket-shaped portions 20 of the blades 15 is disposed centrally of the fan and secured in place to the forward or discharge side of the fan, as by means of screws 26, or in any other suitable or preferred manner. In the illustrated embodiment of the 40 invention, the forward or leading edge of each blade is thickened slightly or provided with a boss, as shown at 27, adjacent the outer end of the scooped portion 20, and these thickened portions or bosses 27 have tapped openings 28 into which 45 screws 26 are threaded to secure the disc 25 in centered position on the discharge side of the fan. The blades 15 are preferably undercut, as shown at 29 (Figures 2 and 3), so that the disc 25 lies flush with the forward or leading edges of 50 55 the blades 15 at the discharge side of the fan.

The outer periphery of the disc 25 lies substantially along the sections 19 where the inner ends of the outer blade portions 17 of constant pitch and curvature meet the outer ends of the inner 60 scooped or bucket-shaped blade portions 21. With this disc 25 thus arranged, the fan is prevented from drawing air in centrally from the discharge side. And, at the same time, pockets 65 70 75 are formed behind the disc 25, there being one such pocket 30 between the disc 25 and each inner scooped or bucket-shaped blade portion 21.

These pockets 30 catch or scoop up the air or other fluid which is thrown outwardly of the inner scooped or bucket-shaped portions 21, and to the outer blade portions 17 by the centrifugal motion. The outer blade portions 17 extend beyond the disc 25 and throw the air or other fluid forwardly. The present improvement provides a much greater velocity of the air at the outside edge of 75 the disc 25, in addition to preventing the fan from

drawing air in centrally from the discharge side thereof. And this is all accomplished by the simple expedient of the disc 25 centrally disposed and secured in place to the discharge side of the fan and, in its more specific aspects, by the combination of this disc with the blade structure illustrated and described. The disc 25 is also adapted for closing the opening through the hub 14 on the discharge side of the fan, so that this opening may extend entirely through the hub 14 without exposing the same at the discharge side of the fan. 5

The thickness of each blade 15 may be progressively increased from the outer tip 18 to the point 16 where the blade is joined to the hub, as disclosed in my last mentioned copending application. As explained therein, this serves to provide the proper proportioning of the blade and disposes the center of gravity at the hub, reducing the 10 inertia and producing less centrifugal force. 15 20

Each blade 15 may be provided on its back side and substantially centrally between its leading and trailing edges with a thickened strengthening rib 35 extending from the tip of the blade to the section 16 which connects the blade to the hub 25 of the fan. These ribs 35 conform to the formation of the backs of the blades and impart the desired strength and rigidity to the blades which, otherwise, may be relatively thin.

I do not intend to be limited to the precise details shown or described, except as set forth in the appended claims. 30

I claim:

1. A fan comprising a hub, a plurality of blades 35 extending from said hub, each of said blades having an outer portion of substantially constant pitch and curvature and an inner generally scooped portion, and means secured to the fan adjacent one side of said inner scooped portions of the blades and covering only the inner scooped portions of said blades at the discharge side of the fan and of a radial extent to leave the outer blade portions of constant pitch and curvature open at the discharge side of the fan, said inner scooped portions extending laterally to said 40 45 means.

2. A fan comprising a hub, a plurality of blades extending from said hub, each of said blades having an outer portion of substantially constant pitch and curvature and an inner generally 50 55 scooped portion, a disc covering only the inner scooped portions of said blades at the discharge side of the fan and of a radial extent to leave the outer blade portions of constant pitch and curvature open at the discharge side of the fan, and means securing said disc peripherally to the leading edges of the blades adjacent one side of the inner scooped portions of the blades, said inner scooped portions extending laterally to said 60 disc.

3. A fan comprising a hub, a plurality of blades extending from said hub, each of said blades having an outer portion of substantially constant pitch and curvature and an inner generally 65 70 75 scooped portion, a disc covering only the inner scooped portions of said blades at the discharge side of the fan and of a radial extent to leave the outer blade portions of constant pitch and curvature open at the discharge side of the fan, and means securing said disc peripherally to the leading edges of the blades adjacent one side of the inner scooped portions of the blades, the blades being undercut so that the disc lies flush with the leading edges of the blades, said inner 80 85 90 95 98

scooped portions extending laterally to said disc.

4. A fan comprising a hub, a plurality of blades extending from said hub, each of said blades having an outer portion of substantially constant pitch extending from the tip of the blade to a point substantially midway between the tip of the blade and the axis of the fan, an inner blade portion of scooped formation inwardly of each of said outer blade portions, connecting portions

10 between the inner ends of said scooped blade

portions and the hub, and a disc secured to the fan adjacent one side of the inner scooped portions of the blades and covering only the inner scooped and connecting portions of the blades and the hub at the discharge side of the fan and terminating peripherally at approximately the inner ends of the outer blade portions of substantially constant pitch, said inner scooped portions extending laterally to said covering means.
